Primary Examiner — Richard E Chilcot*(74) Attorney, Agent, or Firm* — Blue Filament Law PLLC(57) **CLAIM**

The ornamental design for a tractor, as shown and described.

DESCRIPTION

FIG. 1 is a right side view of a tractor showing the new design;

FIG. 2 is a perspective view thereof;

FIG. 3 is a front view thereof;

FIG. 4 is a left side view thereof;

FIG. 5 is a rear view thereof; and,

FIG. 6 is a top view thereof.

The broken line showing of tires, logos, and accessories are for the purpose of illustrating context and form no part of the claimed design.

1 Claim, 6 Drawing Sheets(56)
